Sawyer & Clark.

Peg Rasp.

NO. 10,316.

Patented Dec. 13, 1853.

UNITED STATES PATENT OFFICE.

JOSEPH SAWYER AND LYMAN CLARK, OF ROYALSTON, MASSACHUSETTS.

PEG-RASP.

Specification of Letters Patent No. 10,316, dated December 13, 1853.

To all whom it may concern:

Be it known that we, JOSEPH SAWYER and LYMAN CLARK, of South Royalston, in the county of Worcester and State of Massachusetts, have invented certain new and useful Improvements in Instruments for Removing Pegs from the Interior of Boots and Shoes, called "Peg-Rasps;" and we hereby declare the following to be a full, clear, and 10 exact description of the same, reference being had to the annexed drawings, making part of this specification, in which—

Figure 1 is a view of the rasp, Fig. 2 a longitudinal section through the center of 15 the same.

In instruments of this character as heretofore constructed the rasp has usually been secured permanently to its handle at an angle suitable to enable it to reach the pegs 20 in the toes of the boot; when thus set it acts very imperfectly upon those in the heel, and a separate instrument is sometimes made use of for removing these.

The attempt has been made to unite these 25 two instruments in one by hanging the rasp upon a pivot, so as to enable it to assume any required position to operate upon either the toe or heel of the boot, but this has failed to accomplish the desired end, for 30 want of that stiffness and stability necessary to the successful operation of the instrument.

The nature of our invention consists in 35 hanging the rasp upon a pivot, and adapting thereto a spring bolt, by which means it may be securely fastened in one of two positions, so that the same instrument may be instantaneously adapted to work either in the heel or the toe of the boot.

40 To enable others skilled in the art to make and use our invention we will proceed to describe its construction and operation.

A is the handle of the instrument, B the metallic ferrule, C the rasp pivoted at a. 45 Upon the lug or ear b of the rasp are two holes c—c', into which fits the spring bolt

d—this bolt passes longitudinally through the handle and is secured to the thumb piece e, which has a limited motion in the slot D.

50 f is a spiral or other spring for the purpose of keeping the bolt d, pressed against the ear of the rasp.

55 Operation: The instrument is first used in the position seen in Figs. 1 and 2 for the purpose of taking the pegs from the heel of the boot—then while the boot is still held upon the rasp with one hand, the thumb piece e is depressed with the other, and the bolt d is withdrawn from the hole c; the 60 rasp is then, without removing the boot, instantaneously revolved into the position represented in dotted lines in Fig. 2, when the bolt springs into the hole c', and the instrument is in order for operating within 65 the toe of the boot.

The peg rasp as thus constructed has all the advantages possessed by the old instrument, together with the capability of being used in both heel and toe, and without removing it from the boot, to change it from 70 one position to the other.

We do not claim hanging the rasp of a 75 tool for cleaning out pegs from the inside of shoes and boots upon a pivot and allowing it to adjust itself to the position required, as this has been done before, and is furthermore liable to several objections, the removal of which is the object of our present invention; but

80 What we do claim as new and desire to secure by Letters Patent is—

The combination of the spring bolt and thumb piece or their equivalents with the pivoted rasp—constructed and operating in 85 the manner and for the purpose substantially as described.

JOSEPH SAWYER.
LYMAN CLARK.
